UNITED STATES PATENT OFFICE.

CALEB C. DULA, OF YONKERS, NEW YORK.

METHOD OF MANUFACTURING TOBACCO CARTRIDGES.

1,282,779.

Specification of Letters Patent. Patented Oct. 29, 1918.

Application filed December 18, 1915. Serial No. 67,548.

To all whom it may concern:

Be it known that I, CALEB C. DULA, a citizen of the United States, residing at Yonkers, in the county of Westchester and State of New York, have invented new and useful Improvements in Methods of Manufacturing Tobacco Cartridges, of which the following is a specification.

My present invention relates to an improved method of manufacturing tobacco cartridges for use in smoking pipes, and more particularly to smoking cartridges of the kind, and having the characteristics described and claimed in my Patent Number 1,165,000, dated December 21st, 1915.

The object of the present invention is to provide a simple method of manufacturing tobacco cartridges for use in smoking pipes wherein such manufacture may be carried on by a continuous process so that the resulting product will not only be uniform, but the manufacture of the product may be carried out expeditiously and in a comparatively inexpensive manner.

While one or more of the steps of my improved method may appear to resemble, in a way, one or more of the steps employed in some of the known methods of manufacturing cigarettes from a continuous rod of tobacco, yet my said method differs materially from cigarette manufacture and is clearly distinguished therefrom in certain essential steps of the method, all as will hereinafter appear, and as will be further evidenced by the fact that the resultant product of my method does not, in any way, resemble a cigarette, but is clearly distinguished therefrom in its physical characteristics, its method of use, and its smoking and burning qualities and properties.

Briefly and generally stated, the invention of the present application resides in the method of making smoking cartridges adapted to be smoked in a smoking pipe, which consists in showering previously conditioned tobacco particles to form a stream of tobacco of substantial dimensions wherein the tobacco particles are indiscriminately arranged; continuously advancing the tobacco stream as it is formed; then subjecting the advancing stream to sufficient pressure to cause the tobacco particles to become compacted and interlocked, and thus form a substantially stable, but not densely solidified filler-rod having a cross-sectional shape and

diameter to fit snugly within the bore of the pipe in which it is to be smoked; then continuously applying a close-fitting wrapper-strip of smokable material to the advancing rod and sealing the same while the tobacco particles are in compacted rod form so that the wrapper will closely hug the filler-rod, and finally severing the wrapped rod transversely to provide relatively short pipe-length sections, from the ends of which the tobacco particles will not readily sift.

In order that my invention may be clearly understood, I will proceed to describe the same in connection with the accompanying drawings wherein I have shown, in a somewhat conventional way, certain portions of one form of mechanism that may be employed in carrying out the various steps of the method in a continuous manner.

In the said drawings:

Fig. 1, is a longitudinal vertical sectional view showing the different stages or steps of the continuous method of producing smoking cartridges according to the present invention.

Fig. 2, is a transverse vertical section on the line 2—, Fig. 1, showing the tobacco as it is showered onto a carrier to provide an advancing tobacco stream which is ultimately formed into a rod from which the finished cartridges are severed.

Fig. 3, is a transverse vertical section on the line 3—, Fig. 1, showing the step of imparting to the stream of tobacco the maximum compression to convert the stream into a substantially stable, but not densely solidified rod, and by which compression the tobacco particles are caused to become interlocked.

Fig. 4, is a transverse vertical section on the line 4—, Fig. 1, showing how the rod of tobacco expands after it has passed the maximum compression stage of the method and just prior to the application of the wrapper-strip thereto.

Fig. 5, is a transverse vertical sectional view on the line 5—, Fig. 1, showing the wrapper-strip partially applied to the rod with one edge of the strip upstanding to receive a stripe of paste to form the sealed seam of the rod.

Fig. 6, is a transverse vertical sectional view on the line 6—, Fig. 1, showing the tobacco rod with its applied wrapper wrapped thereabout and the seam sealed.

Fig. 7, is a perspective view of one of the finished cartridges after it has been cut from the rod.

Fig. 8, is a transverse sectional view showing the stream of tobacco of substantial dimensions just before it is compressed into rod form.

Fig. 9, is a similar view showing the stream reduced to rod form, the rod being under maximum compression, this step of the method operating to cause the tobacco particles to become interlocked.

Fig. 10, is a similar view of the tobacco rod just after it leaves the maximum compression stage and showing how the rod of tobacco expands after leaving the said compression stage.

Fig. 11, is a similar view of the tobacco rod showing the wrapper partially applied thereto.

Fig. 12, is a similar view showing how the tobacco rod is further compressed to its final shape and inclosed and retained within its wrapper.

Fig. 13, is a perspective view showing one of the compacted cartridges standing alone, the wrapper having been removed.

Fig. 14, is a perspective view of one of the cartridges broken open to show, in a way, how the particles of tobacco have been interlocked by the maximum compression step of the method.

Fig. 15, is a view showing how a certain definite length of rod may be simultaneously cut into a plurality of pipe-length sections or cartridges, according to a modified arrangement of the method as distinguished from cutting individual cartridges from the rod as it is formed.

Fig. 16, is a perspective view of one form of package containing a plurality of my improved cartridges arranged end to end to form a handy pocket package.

Fig. 17, is a view partly in section of an ordinary pipe showing one of my improved cartridges inserted therein, the view showing how the cartridge fits snugly into the pipe and how it is slightly compressed during such insertion.

In practising my improved method according to the present invention, I first treat the tobacco leaves or leaf strips in a suitable way to render them soft and pliable. This may be accomplished by moistening or steaming the leaves or strips, and if desired, a suitable "casing" or flavoring extract in the form of a solution may also be employed. This however, is optional with the manufacturer. The softened tobacco leaves are then cut up to provide the tobacco particles from which the cartridges are to be formed, the said particles preferably consisting of relatively short slivers of tobacco of non-uniform dimensions, some being shorter than others. I do not, how-

ever, wish to be understood as confining myself to any particular manner of cutting the tobacco except that the tobacco particles, or at least some of them, should be of such dimensions or form as to be capable of becoming interlocked with others so as to form a substantially stable rod when subjected to the proper degree of compression.

The soft and pliable tobacco particles are first continuously formed into a stream of relatively large dimensions, the stream being preferably formed by showering the tobacco particles onto a traveling carrier 12, and between spaced moving side walls 13 to collect the tobacco into the form of a stream of substantial dimensions wherein the particles of tobacco constituting the stream are indiscriminately arranged. The stream of conditioned tobacco may be formed in any desired way, but I prefer to first deposit the tobacco particles in a thin layer upon a somewhat rapidly moving endless belt 14 from which the particles are beaten off by a brush-like beater 15 and showered through a vertically arranged trough 16 into the channel formed by the carrier belt 12 and the two moving side walls 13 hereinbefore referred to, which constitute the said channel for determining the dimensions of the moving stream 10 of tobacco, this channel preferably converging from its rear end toward the forward end so that the advancing stream is gradually compressed laterally as it is formed and advanced.

This advancing stream of indiscriminately arranged tobacco particles is then subjected to considerable pressure preferably applied on radial lines, and this may be effected by causing the stream to move or travel between suitable compressing devices which may consist in part of the endless carrier 12 and moving side walls 13 of the channel heretofore referred to, and in part of a grooved presser wheel 17, as more clearly shown in Figs. 1 and 3. This I may term the maximum compression stage of the method and is an important step in the process because of the effect it has upon the tobacco particles. These parts are so shaped, combined and adjusted as to cause the advancing stream of tobacco to be so closely compacted as to cause the tobacco particles to become interlocked and at the same time the stream is formed into a substantially cylindrical rod 18, Figs. 1, 3 and 9. The degree of compression, however, is not so great as to form a rod that is densely solidified. Owing to the condition of the tobacco particles, which are, as stated, so treated as to render them more or less inherently yieldable or springy, the compacted rod has a tendency to expand considerably after leaving the point of maximum compression, as shown at 19, Figs. 4 and 10.

I take advantage of this peculiar action of the tobacco, which results in part from the manner in which the tobacco particles have been treated or conditioned, and in part 5 from the degree of compression to which the stream has been subjected, in order to bring about a close application or snug fit of the wrapper-strip 20 to the advancing rod of tobacco. The said wrapper-strip 20 is preferably composed of rice paper which, owing to the fact that it is thin and flexible, may be wrapped closely about and caused to tightly 10 embrace the rod, as distinguished from a more or less loose fit about the rod such as 15 would permit of the tobacco being readily expelled from its wrapper; as is the case with cigarettes as commonly manufactured, and as contemplated in suggested forms of tobacco cartridges described in various prior 20 art patents which have come to my attention and from which my improved cartridge is clearly distinguished.

As the expanded rod 19 of compacted and interlocked tobacco particles leaves the 25 maximum compression stage referred to, it is continuously advanced or carried forward in any suitable way, as by means of the endless tape 21, Fig. 1, and during its forward movement or travel the paper 30 wrapper-strip 20 is continuously wrapped or rolled about the tobacco rod, one edge of the moving wrapper-strip being left upstanding to receive a stripe of paste applied thereto as by a roller 22, Figs. 1 and 5, to form 35 the seam of the wrapper, which seam is formed by folding over and pasting the edge having the stripe of paste to the unpasted edge of the wrapper. To effectually close and smooth the seam and assist in drying 40 the paste, I may rub the freshly pasted seam with a rapidly rotating brush 23, as more clearly shown in Fig. 1.

During the operation of applying the wrapper-strip to the advancing rod of tobacco, the said rod is preferably subjected 45 to further compression to again reduce the diameter thereof, so that the finished rod and the cartridges cut therefrom will have a diameter slightly in excess of the diameter of 50 the rod at the point of maximum compression, as shown in Fig. 12, the said finished cartridges 24 having a cross-sectional shape and diameter substantially coextensive with the shape and diameter of the bore of the 55 pipes, as 25, in which they are to be smoked.

The effect of the further compression of the tobacco rod as above referred to is to cause the thin paper wrapper to be closely applied or stretched about the rod, so that 60 not only will the wrapper be close-fitting, but the tobacco particles will not readily sift from the ends of a short section or cartridge cut therefrom notwithstanding the diameter of the cartridges which are nearly 65 as thick through as they are long.

As the finished rod advances, the individual cartridges 24 are cut therefrom as by a rotary cutter 26, Fig. 1, or if desired, I may cut sections of substantial length from the rod and subsequently cut such severed 70 length into a plurality of short pipe-length sections or cartridges 24, such cutting being effected simultaneously by means of a plurality of disk-like cutters 26^a, Fig. 15.

In Figs. 8 to 12 inclusive, I have shown 75 cross-sectional views of the tobacco stream and rod formed therefrom during the several successive steps or stages of the method.

By referring to these figures, it will be seen that in Fig. 8 the tobacco particles are 80 indiscriminately arranged and collected in the form of a stream 10 having substantial cross-sectional dimensions.

In Fig. 9, the stream is shown at what I have termed the maximum compression 85 stage 18, at which point the tobacco particles are subjected to sufficient pressure, preferably exerted on radial lines, to cause the particles to become interlocked, the interlocking action being due in part to the 90 degree of compression exerted upon the tobacco particles, and in part to the form and condition of the tobacco particles.

In Fig. 10, at 19, the rod is shown just after it leaves the maximum compression 95 stage and it will be seen by referring to said figure that notwithstanding the degree to which the tobacco has been compressed or compacted, the rod nevertheless expands considerably owing to the springy nature of 100 the tobacco, the fact that it has been closely compacted and the manner and extent to which it has been rendered pliable.

In Fig. 11, the wrapper-strip 20 is shown partially applied to the rod, and in Fig. 105 12, the wrapper is shown as completely applied and the seam sealed.

As before stated, during the steps of applying the wrapper to the rod, the latter is further compressed which further compression may be effected by passing the rod with its wrapper-strip through the substantially rigid channel 27, as more clearly shown in Figs. 1 and 6, so that when the closely compacted rod with its applied and seamed 110 wrapper emerges from the channel 27, the inherent expansibility of the tobacco particles again asserting itself will cause the wrapper to become more closely applied, or in other words, will cause the rod to become 115 more closely confined and retained within its wrapper so that not only will the particles of tobacco be prevented from sifting out of a short section or cartridge cut from the rod, but the rod itself cannot be readily 120 expelled from its wrapper.

While the rod of tobacco is subjected to considerable pressure as referred to, so as to cause the tobacco particles to become interlocked and form a substantially stable 130

rod, yet the compression is not so great as to entirely destroy the porosity of the rod or prevent a draft therethrough, as is required when smoking the cartridges in a pipe. The 5 tobacco particles, however, are sufficiently closely compacted so that an uncovered section of the rod or cartridge will maintain its shape against moderate pressure when standing alone, as more clearly shown in 10 Fig. 13.

Fig. 14 illustrates one of the wrapped cartridges broken open longitudinally and illustrating in a way how the tobacco particles become interlocked during the compression 15 stage or stages of the method.

In preparing the cartridges for the market, I prefer to arrange a plurality of the cartridges end to end and inclose them within a wrapper blank 28 of flexible and substantially air and moisture-proof paper, as more 20 clearly shown in Fig. 16. The wrapper blank 28 is wound or curled about the series of individual cartridges 24 and the free ends of the blank neatly folded and sealed to 25 form a handy pocket package. In wrapping the cartridges, the individual cartridges cut from the rod may be arranged end to end as described and then wrapped; or I may cut a section from the rod of sufficient length 30 to provide a plurality of cartridges, which rod length or section may then be simultaneously acted upon by suitable cutters 26^a to cut the same into a plurality of cartridges, as more clearly shown in Fig. 15, and without 35 disarranging the end to end relation of the cartridges so cut, I may then wind or roll the wrapper blank about the same and seal the blank to form the handy pocket package referred to.

40 In Fig. 17, I have illustrated an ordinary form of smoking pipe 25 having one of my improved cartridges 24 inserted therein, the view showing how the cartridge, notwithstanding the fact that the tobacco therein 45 has already been very closely compacted, yet it is still susceptible of slight further compression whereby the cartridges may be inserted within the bowl of the pipe so as to have a snug fit therein.

50 It will be seen from the foregoing that according to my improved method, I am able to manufacture in a continuous, comparatively inexpensive, and expeditious manner, tobacco cartridges composed of 55 tobacco particles indiscriminately arranged, and wherein each cartridge is sufficiently closely compacted to maintain its shape against moderate pressure when standing alone, as shown in Fig. 13, but so packed 60 as to permit of slight further compression when forced into a smoking pipe and form a snug fit therein and allow of a draft therethrough, the said cartridges being each of substantially uniform diameter from end 65 to end and inclosed within an open-ended

wrapper having a sufficiently snug fit to prevent displacement of the wrapper on the cartridge when the covered cartridge is forced into a pipe or smoking tube.

Tobacco cartridges for use in smoking 70 pipes made in accordance with my improved method as herein described, are clearly distinguished from all known forms of cartridges and methods of making the same of which I am aware, and are clearly distinguished from cigarettes or cigarette manufacture in that not only are the cartridges made in relatively short sections and of sufficient diameter to fit snugly within a smoking pipe, but the tobacco particles are 75 so conditioned, arranged and compacted as to become interlocked and thus form a substantially stable, but not densely solidified filler having sufficient porosity to permit of a draft therethrough, and the particles are 80 also prevented from sifting out of the ends of the wrapped cartridge thus avoiding the objectionable "soggy heel" so common in ordinary pipe smoking.

Furthermore, owing to the manner in 90 which the tobacco particles are compacted, the cartridges will burn slowly and evenly, thus giving the consumer a relatively long and cool smoke from a very short section or cartridge. Another advantageous characteristic of cartridges made according to 95 my method is that the ash of the burning cartridge maintains its cartridge form during the act of smoking, thus affording a clean smoke since the burning tobacco does 100 not expand and slough out over the edge of the pipe as is the case with pipes loaded in the ordinary way. A still further advantage resulting from the peculiar manner in which 105 the tobacco is arranged and compacted resides in the fact that the cartridges may be said to be "ready tamped" thus avoiding the necessity of continually packing or tamping the burning tobacco during the act of smoking as is customary and necessary with other 110 forms of tobacco.

What I claim is:

1. The method herein described of making smoking cartridges adapted to be smoked in a smoking pipe, which consists in showering 115 tobacco particles to form a stream of substantial dimensions wherein the tobacco particles are indiscriminately arranged, continuously advancing the stream as it is formed, then subjecting the advancing stream to sufficient pressure to cause the tobacco particles to become interlocked and thus form a substantially stable, but not densely solidified 120 filler-rod, the pressure exerted upon the tobacco being sufficient to cause a short section 125 cut from the rod to maintain its shape against moderate pressure when standing alone, then continuously applying a close-fitting wrapper-strip of smokable material to the advancing rod and sealing the same 130

while the tobacco particles are held in compacted rod form, and finally severing the wrapped rod transversely to provide relatively short pipe-length sections having a 5 cross-sectional shape and diameter to fit snugly within the pipe in which it is to be smoked.

2. The method herein described of making smoking cartridges adapted to be smoked in 10 a smoking pipe, which consists in arranging previously conditioned tobacco particles in the form of a stream of substantial dimensions wherein the said particles are indiscriminately disposed relative to one another, continuously advancing the stream as 15 it is formed, then subjecting the advancing stream to sufficient pressure to cause the tobacco particles to become interlocked and thus form a substantially stable but not 20 densely solidified filler-rod, the said pressure exerted upon the rod being sufficient to cause a section cut from the rod to maintain its shape against moderate pressure when standing alone, then applying a close-fitting 25 wrapper-strip of smokable material to the rod and sealing the same while the tobacco particles are held in compacted rod form, and finally severing the wrapped rod transversely of its length to provide relatively 30 short pipe-length sections each having a cross-sectional shape and diameter to fit snugly within the pipe in which it is to be smoked.

3. The method herein described of making 35 smoking cartridges adapted to be smoked in a smoking pipe, which consists in showering previously conditioned tobacco particles to form a stream of substantial dimensions wherein the tobacco particles are indiscriminately arranged, continuously advancing the stream as it is formed, then subjecting the advancing stream at one point to sufficient pressure exerted upon radial lines to cause the tobacco particles to become interlocked 40 and thus form a substantially stable but not densely solidified filler-rod, the said pressure 45

exerted upon the tobacco being sufficient to cause a short section cut from the rod to maintain its shape against moderate pressure when standing alone, then permitting 50 the compressed rod to expand, then again compressing the rod to a cross-sectional shape and diameter to fit snugly within the pipe in which it is to be smoked and while in such later compressed state continuously 55 applying a close-fitting wrapper-strip of smokable material thereto and sealing the same, and finally severing the wrapped rod transversely to provide short pipe-length 60 sections.

4. The method herein described of making smoking cartridges adapted to be smoked in a smoking pipe, which consists in showering tobacco particles to form a stream of substantial dimensions wherein the tobacco particles are indiscriminately arranged, continuously advancing the stream as it is formed, then subjecting the advancing stream to sufficient pressure to cause the tobacco particles to become interlocked and 65 thus form a substantially stable, but not densely solidified filler-rod, then permitting the rod to expand slightly, then further compressing the rod to bring it to a cross-sectional shape and diameter to fit snugly 70 within the pipe in which it is to be smoked and while so compressed applying a close-fitting wrapper-strip thereto, then severing the wrapped rod transversely into a plurality of pipe-length sections arranged end to 75 end, and finally inclosing the said plurality of sections within an outer wrapper or cover without disarranging the end to end relation of the cartridges to provide a handy pocket package.

In testimony whereof I have hereunto set my hand in presence of two subscribing witnesses.

CALEB C. DULA.
